UNITED STATES PATENT OFFICE
ISSUED

LEON OTTINGER, OF NEW YORK, N. Y.

LATCH ESCUTCHEON AND METHOD OF APPLYING THE SAME.

Application filed June 28, 1923. Serial No. 648,394.

To all whom it may concern:

Be it known that I, LEON OTTINGER, a citizen of the United States, and a resident of the city, county, and State of New York, have invented certain new and useful Improvements in Latch Escutcheons and Methods of Applying the Same, of which the following is a specification.

This invention relates to an improved latch escutcheon and method of applying the same and has more particular relation to such escutcheons as are used in connection with the latches of automobile doors. Heretofore, it has been the practice to provide a relatively long cast metal bushing threaded or otherwise fixed in the outer end of the handle receiving opening of the door to provide a bearing for the handle, said bushing having a flange or escutcheon plate formed on one end to engage against the face of the door around the latch handle. However, in view of the fact that the inner and outer faces of the door are not parallel, and the wall of the opening does not extend at right angles to the outer face of the door, it is impossible to secure close contact of an escutcheon plate or flange of uniform thickness against the door face entirely around the opening. In other words, at one side of the opening in the door the plate would be slightly spaced from the door face, unless said plate is specially formed and thickened upon one side. Escutcheon members of this type are, therefore, relatively expensive. Also, these escutcheon plates are provided with openings to receive attaching screws threaded in the door which is an additional item of expense.

It is, therefore, the primary object and purpose of my present invention to provide a combined escutcheon and shaft bearing member for door latch handles and a method of applying the same to the door whereby close contact of the escutcheon against the door face entirely around the opening is assured with a proper accurate alignment of the opening of the escutcheon member with respect to the latch actuating rollback to which the handle is to be connected, regardless of the angular relation of the wall of the handle receiving opening with respect to the face of the door.

In one embodiment of the invention, I provide an escutcheon member, which, when applied and secured to the door provides a

tangential single point bearing contact for the shank of the latch handle. Preferably, the escutcheon member is initially in the form of a sheet metal sleeve having an out-turned rounded bead or other ornamental formation on one end thereof adapted to bear against the outer face of the door around the handle opening therein. In the application of this escutcheon member to the door, I position the same against the door face with the sleeve extending into the handle opening and then properly center said sleeve in concentric relation with the latch actuating rollback. While maintaining pressure against the outer face of the escutcheon member to hold the edge member thereof closely against the door face, I then apply an outward pressure against the inner wall of the inwardly extending part of said member whereby the latter is expanded and the edge thereof is firmly embedded in the wood structure of the door. Thus the escutcheon member is tightly and securely fixed in place at the outer end of the handle opening without the use of screws or other supplemental fastening or attaching means.

It is another object of my invention to provide a combined escutcheon and handle bearing which is of such construction that it may be used in connection with the various types of latches now employed upon automobile doors and will decrease the number of operations required in the application of such latches while providing a neater appearance on the outer face of the door around the latch handle than is possible with the use of such devices now employed in this art.

With the above and other objects in view, the invention consists in the improved escutcheon member and in the manner of applying the same to the door, as will be hereinafter more fully described, illustrated in the accompanying drawing and subsequently incorporated in the subjoined claims.

In the drawing wherein I have disclosed several practical and desirable embodiments of the invention and in which similar reference characters designate corresponding parts throughout the several views:

Figure 1 is a horizontal section through an automobile door having a latch applied thereto and equipped with one embodiment of my present improvements;

Figure 2 is a similar section showing the

initial form of the escutcheon member before securing the same in its final position in the door;

5 Figure 3 is a sectional view illustrating the centering and expanding tool for the sheet metal escutcheon member;

Figure 4 is an inner face view of the escutcheon member in its original form; and

10 Figures 5 and 6 are detail sections illustrating several alternative forms of the device.

While the invention to be hereinafter described is more particularly designed for application and use in connection with the 15 doors of automobiles, it will be apparent that the device might also be advantageously used in connection with the latch handles of house doors and in other cases where it is desired to provide a bearing support for the 20 operating handle and a neat and attractive appearance of the outer face of the door surrounding said handle. In the present instance, I have illustrated a part of an automobile door 5 to the inner face of which a 25 latch 6 is applied. As this latch constitutes no essential feature of the present improvements, it may be of any desired construction. For the purpose of this explanation it will suffice to state that the latch mechanism 30 includes an actuating rollback 7 which is suitably mounted in the walls of the latch case for oscillating or rotative movement. The rollback 7 is operated by means of the usual handle 8 and as herein shown, one end 35 of this handle is rigidly fixed in the bore of the rollback by means of the screw 9. Likewise, this handle attaching means constitutes no essential part of the present improvements, the same being fully described and 40 claimed in my co-pending application for patent, Serial No. 613,809, filed January 20, 1923.

It will be observed from reference to Figure 1 of the drawing that the outer face 10 45 of the door is not disposed in parallel relation to the inner face thereof. Therefore, if the handle receiving opening 11 is bored through the door with its outer end in concentric relation with the axis of oscillation 50 of the rollback 7, it will be apparent that the axis of the opening does not extend at right angles to the door face 10. Accordingly, if a rigid metal bushing having an escutcheon flange or plate on its outer end 55 is threaded into the opening 11, said flange or plate can be brought into close contact with the face 10 of the door only at one side of the opening 11. Various suggestions have been advanced for remedying this difficulty. 60 Thus it has been proposed to use a separate escutcheon plate, loosely mounting the same on the outer end of the bearing bushing, and interposing a spring between said plate and a washer engaging the door around the handle opening. It will be apparent, however,

that such a device will be quite expensive and that it is also impossible to attain a tight or close contact of the escutcheon plate with the handle shaft.

In one embodiment of my present improvements, I provide a combination escutcheon and shaft bearing member 12 in the form of a sheet metal stamping, said member consisting of the sleeve 13 having an outwardly turned semi-cylindrical annular 75 flange or bead 14 formed on one end thereof. As seen in Figure 2 of the drawings, the diameter of the sleeve 13 is appreciably less than the diameter of the opening 11 and in the application of the member 12 to the door, so the edge of the flange or bead 14 is closely engaged against the door face 10 entirely around the opening 11 while the sleeve 13 projects into said opening. While I have referred to the escutcheon member as having 85 the semi-cylindrical bead 14 it will, of course, be obvious that since this formation of the sleeve end is purely for purposes of ornamentation, the sheet metal plate from which the device is produced might be of greater area and formed with an escutcheon plate or flange extension of any desired ornamental configuration to extend over a greater area of the door face 10.

After the escutcheon and bearing member 95 has been positioned, as seen in Figure 2 of the drawings, the expanding tool 15 illustrated in Figure 3, is then applied. This expanding tool may be of any conventional construction, but as illustrated is provided 100 with a plurality of pivotally mounted expanding members 16 between which a conoidal expanding head 17 is arranged. Each of the members 16 has a reduced deeply grooved or concaved end portion 18. The 105 expanding head 17 is preferably provided with a socket to receive the end of the centering rod 10 which is detachably fixed in said socket by the screw 20.

In arranging the expanding tool in position, the members 16 are positioned against the escutcheon flange or bead 14 with their reduced end portions 18 extending through the sleeve 13. In order to insure a concentric relationship of the sleeve 13 with the axis of the latch actuating rollback 7, the end of the centering rod 19 is engaged in the bore of said rollback. The expanding tool 15 is then operated to force the members 16 radially outward so that their concave end portions 18 will exert an expanding pressure against the sleeve 13 extending into the opening 11. Thus this end of the sleeve will be outwardly expanded and the edge thereof firmly embedded in the wood structure of the door 5 around the opening or passage 11 extending therethrough. In this expanding action, it will be understood 120 that the members 16 of the tool bearing against the escutcheon flange or bead 14 125 130

holds the edge thereof in close bearing contact against the door face 10. Thus at all points around the outer end of the opening 11 the escutcheon flange will be in positive 5 contact with the face of the door. After the expanding tool is removed the member 12 is then in the form of a tubular annulus 10 open at one side thereof with one edge of said open side extending into the opening 11 of the door and embedded in the door structure. Thus, as seen in Fig. 1 of the drawing, when the operating handle 8 for the latch rollback 7 is inserted and secured to said rollback, the handle shank will have 15 a single circumferential point of bearing contact upon the inner face of the tubular escutcheon at 21. In Figure 1 of the drawing, I have illustrated the opening 11 in the door having its outer end concentric 20 with the rollback 7, while in Figures 2 and 3 of the drawing, the opening 11 is supposed to have been inaccurately bored through the door so that its outer end is eccentric to the rollback. In the latter instance, it 25 will be understood that the proper centering of the sleeve 13, before expansion in the end of the opening 11, is essential in order that the shank of the handle may be properly fitted or mounted in the escutcheon and 30 bearing member after its application to the door.

In Figure 5 of the drawing, I have shown a slightly modified form of the device in which the sleeve 13' is of greater length 35 to provide a relatively long straight intermediate bearing portion 21' for the handle shaft instead of the single point circumferential contact above referred to. Also, in this case, I may embed the outer edge of the 40 escutcheon bead or flange in the face of the door as shown at 22, as well as expanding the inner end edge of the sleeve 13' into the door structure.

In automobile door latches having the 45 solid metal sleeve or bushing threaded into the outer end of the handle opening, such bushing is usually provided with an internal annular shoulder intermediate of its ends against which a shoulder formed on 50 the handle shank seats. In order to adapt my invention for use in connection with latches having such a shouldered handle shank, I may provide the construction shown in Figure 6 of the drawings wherein 55 the sleeve is provided at the inner side of the semi-tubular escutcheon flange or bead 14' with an inwardly projecting annular shoulder 23. The reduced end portion of the sleeve indicated at 13' is expanded to 60 embed its edge in the door structure, and the expanding tool may be of such form as to also contract the semi-tubular bead or escutcheon flange 14' slightly and thus embed 65 the sharp circumferential edge 24 formed at the juncture of said escutcheon

flange with the wall of the shoulder 23 into the wood. These two spaced points of engagement of the metal member in the door structure provides greater security.

From the foregoing description considered in connection with the accompanying drawing it is believed that the construction of my improved escutcheon and handle bearing for door latch handles as well as the method of applying same will be clearly 70 and fully understood. Owing to the fact that after positioning the escutcheon member, it may be firmly and securely fixed upon the door by a single operation of the expanding tool, it will be apparent that the time required in the application of such 75 shaft bearing and escutcheon members is very materially reduced over that necessary in the application of such devices as are now very generally employed in this art. 80 It will further be appreciated that since I eliminate the necessity of using screws or other fastening members, the cost of this item of automobile body construction is very greatly reduced. Also as I altogether 85 discard the threaded bearing bushing heretofore employed, extreme accuracy in the boring of the handle receiving opening in the door structure becomes unnecessary so that there will be a further reduction of 90 time consumed in the application of the latch to the door. These several items when compared with the total manufacturing cost 95 of the individual automobile body may seem quite insignificant, yet in the aggregate they constitute an appreciable item of expense. By eliminating such expensive 100 details, my present invention enables the manufacturer to speed up production, and thus correspondingly decrease his overhead 105 expense.

I have referred in the foregoing description and illustrated in the drawings several forms or embodiments of my present invention which are entirely practical for the purpose in view. Nevertheless, it will be manifest that the same desirable results might possibly be secured by utilizing a combination bearing and escutcheon member of other structural forms than those 110 herein disclosed. Accordingly it is to be understood that I reserve the privilege of resorting to all such legitimate changes in the several novel features of my present improvements as may be fairly embodied 115 within the spirit and scope of the invention 120 as claimed.

I claim:

1. In combination with a door structure having a latch handle receiving opening, a latch operating rollback at one end of said opening and an operating handle adapted to be connected to said rollback; a bearing member for the handle shaft 125 permanently fixed in the door structure at 130

the other end of said opening and having a continuously curved or convex surface presenting a single circumferential line of bearing contact for the handle shaft in 5 tangential relation thereto.

2. In combination with a door structure having a latch handle receiving opening, a latch operating rollback at one end of said opening and an operating handle adapted 10 to be connected to said rollback; a bearing member for the handle shaft permanently fixed in the door structure at the other end of said opening and having a continuously curved or convex surface presenting 15 a single circumferential line of bearing contact for the handle shaft in tangential relation thereto, said member having an integrally formed escutcheon flange closely contacting with the face of the door at all 20 points around said opening.

3. In combination with a door structure having a latch handle receiving opening, a latch operating rollback at one end of said opening and an operating handle adapted 25 to be connected to said rollback; a combined bearing and escutcheon member for said handle consisting of a one-piece metal annulus having an edge thereof in close contact with the face of the door surrounding 30 the other end of said opening and its other edge extending into the opening and embedded in the door structure.

4. In combination with a door structure having a latch handle receiving opening, a latch operating rollback at one end of said opening and an operating handle adapted 35 to be connected to said rollback; a combined bearing and escutcheon member for said handle consisting of a one-piece metal annulus positioned at the opposite end of said opening in concentric relation to the latch rollback and having one of its edges in close contact with the face of the door surrounding 40 the end of said opening and its other edge extending into the opening and embedded in the door structure, said annulus being formed with an inner convex surface presenting a single circumferential line of bearing contact with the handle shaft in 45 50 tangential relation thereto.

5. In combination with a door structure having a latch handle receiving opening, a latch operating rollback at one end of said opening and an operating handle adapted 55 to be connected to said rollback; a combined bearing and escutcheon member for said handle consisting of a tubular sheet metal annulus having a circumferential opening, the edge portion of said annulus at one side 60 of the opening therein extending into the other end of the opening in the door structure and being embedded in the wall of said opening, the other edge of the annulus at the opposite side of the circumferential 65 opening therein closely contacting with the

side face of the door at all points surrounding said opening.

6. In combination with a door structure having a latch handle receiving opening, a latch operating rollback at one end of said opening and an operating handle adapted to be connected to said rollback; a combined bearing and escutcheon member for said handle permanently fixed to the door structure at the other end of the opening therein 70 and consisting of a one-piece sheet metal element having an escutcheon flange formed on one end closely contacting with the face of the door around the end of said opening and an annular portion extending into the opening from said escutcheon flange and having an outwardly turned edge firmly embedded in the wall of said opening and constituting the sole securing means for said member. 75

7. A combined bearing and escutcheon 80 member for door latch handles having a part adapted to be engaged closely upon the door face at all points around the handle opening in the door, and another part to extend within said opening providing a 85 circumferential edge portion adapted to be subjected to an expanding pressure and embedded in the structure of the door. 90

8. A combined bearing and escutcheon member for door latch handles consisting of a sheet metal sleeve adapted to be positioned in one end of the handle opening in the door, said sleeve having an escutcheon flange formed on one end thereof adapted to closely contact with the door face at all 95 points around the opening therein, the other end of said sleeve extending into the opening adapted to be outwardly expanded and embedded into the wood of the door to 100 secure said member in place. 105

9. The method of securing a sheet metal escutcheon member to a door structure having a handle opening extending therethrough at an angle of other than 90° with respect to one face of the door structure 110 which consists in inserting one end of a sheet metal sleeve within the end of said handle opening and engaging a flange on the other end of said sleeve against the face of the door, then applying pressure against the sleeve flange to maintain the edge thereof in close contact with the door face around said opening and simultaneously expanding a part of the sleeve extending into said opening in an outward radial direction and embedding the same in the structure of the door to thereby permanently fix said escutcheon member in position with respect to said handle opening. 115

10. The method of securing a combined latch handle bearing and escutcheon member to a door which consists in first positioning an escutcheon flange on one end of a sheet metal bearing sleeve against the door face surrounding the end of the handle 120 125 130

- opening with the other end of said sleeve projecting into the opening, and then applying pressure against the escutcheon flange to maintain the edge thereof in close contact with the door face and simultaneously expanding the inner end of the sleeve outwardly and embedding the edge thereof in the door structure to thereby firmly secure said member in place.
- 10 11. The method of securing a combined latch handle bearing and escutcheon to a door, which consists in first positioning an escutcheon flange on one end of a sheet metal bearing sleeve against the door face with the other end of the sleeve extending into the handle receiving opening of the door, then applying an expanding tool against said flange to maintain the edge thereof in tight bearing contact with the door face and simultaneously expanding said sleeve outwardly into tubular form and embedding the inner end edge thereof in the door structure.
- 15 12. The method of securing a combined latch handle bearing and escutcheon to a door structure having a latch including an actuating rollback applied to one side thereof, which consists in first positioning the escutcheon flange of a sheet metal bearing sleeve against the face of the door at the other side thereof with said sleeve extending into the handle receiving opening in the door, then applying an expanding tool to said member and centering said sleeve with respect to the latch actuating rollback, and finally expanding the inwardly extending end of the sleeve to embed the
- edge thereof in the door structure while maintaining pressure of the expanding tool against the escutcheon flange to hold the edge thereof in tight contact against the door face.
- 20 13. In combination with a structure having an opening therethrough and a shaft of appreciably less diameter than said opening, a bearing member fixed to said structure at one end of said opening and having an annular convex bearing surface for the shaft concentrically related to the end of said opening and presenting a single circumferential line of bearing contact upon the periphery of the shaft whereby said shaft may be rotatably supported by said bearing member with the axis of said shaft out of coinciding relation with the axis of said opening.
- 25 14. In combination with a structure having an opening therethrough and a shaft extending through said opening, a bearing member for said shaft consisting of a sheet metal annulus having a part embedded in said structure at one end of the opening therein and having a convex portion presenting a single line of circumferential bearing contact upon the periphery of said shaft whereby said shaft may be rotatably supported by said bearing member with a minimum of friction with the shaft axis out of coinciding relation with the axis of said opening.
- 30 35 In testimony that I claim the foregoing as my invention, I have signed my name hereunder.

LEON OTTINGER.
